[57] CLAIM

The ornamental design for van body, as shown and described.

DESCRIPTION

FIG. 1 is a side elevational view of a van body showing my new design;

FIG. 2 is a front elevational view thereof;

FIG. 3 is an enlarged fragmentary perspective view thereof showing the front side window in detail;

FIG. 4 is a top plan view thereof; and

FIG. 5 is a side elevational view thereof opposite to that shown in FIG. 1.

The broken lines in the drawing are for illustrative purposes only.

The rear of the body is substantially flat and unornamented.

FIG. 1

FIG. 2.

FIG. 3.

FIG. 4.

FIG. 5.
